UNITED STATES PATENT OFFICE.

FREDERIC BREWSTER BASSETT, OF WASHINGTON, DISTRICT OF COLUMBIA.

DESIGN FOR A COMBINED TELEPHONE SEAT AND DESK.

Application filed September 15, 1923. Serial No. 7,210. Term of patent 7 years.

To all whom it may concern:

Be it known that I, FREDERIC BREWSTER BASSETT, a citizen of the United States, residing at Washington, in the District of Columbia, have invented a new, original, and ornamental Design for Combined Telephone Seat and Desk, of which the following is a specification, reference being had to the accompanying drawing, forming part thereof.

The figure is a perspective view of a combined telephone seat and desk, showing my new design.

I claim:

The ornamental design for a combined telephone seat and desk, substantially as shown.

FREDERIC B. BASSETT.
